(57) **CLAIM**

The ornamental design for a baitcast-style reel and reel seat umbrella handle, as shown and described.

DESCRIPTION

FIG. 1 is a perspective view of a baitcast-style reel and reel seat umbrella handle showing my new design;

FIG. 2 is an enlarged portion of FIG. 1;

FIG. 3 is a front elevational view of FIG. 2;

FIG. 4 is a back elevational view thereof;

FIG. 5 is a left side elevational view thereof;

FIG. 6 is a right side elevational view thereof;

FIG. 7 is a top plan view thereof; and,

FIG. 8 is a bottom plan view thereof.

The broken lines shown in FIGS. 1-6 are for illustrative purposes only form no part of the claimed design.
